DESIGN FOR A TYPEWRITER

Theodore G. Clement, Rochester, N. Y., assignor to International Business Machines Corporation, New York, N. Y., a corporation of New York

Application December 18, 1947, Serial No. 143,232

Term of patent 14 years

(Cl. D64—11)

To all whom it may concern:

Be it known that I, Theodore G. Clement, a citizen of the United States, and a resident of Rochester, county of Monroe, and State of New York, has invented a new, original, and ornamental Design for a Typewriter, of which the following is a specification, reference being had to the accompanying drawing, forming part thereof.

The figure is a front perspective view of a typewriter showing my new design, the opposite side presenting substantially the same appearance as the side shown.

I claim:

The ornamental design for a typewriter, substantially as shown and described.

THEODORE G. CLEMENT.
